2 Claims

ABSTRACT OF THE DISCLOSURE

A shim insertable in the interlock of a voting machine of the type shown in Shoup patents, U.S. Numbers 2,054,102 and 2,293,669.

The invention

A voting machine of the type referred to, includes an interlock which segregates the candidates running for one office from those running for another office and for limiting the number of votes which can be cast. Because the number of candidates may vary and because the number of votes which may be cast also may vary, it has been necessary to dismantle the interlock after each use and to rebuild it according to the requirement of a subsequent election, even though the number of candidates in the subsequent election happens to be fewer than the number voted on in the preceding election.

The invention solves this problem by providing means for reducing the capacity of the interlock so as to limit the necessity of re-building the interlock to cases where the number of candidates is increased.

In the drawings:

FIG. 1 is a plan view of a shim embodying this invention.

FIG. 2 is similar to FIG. 1 and shows the first step in inserting the shim of FIG. 1 into an interlock section of the type shown in the Shoup patents aforesaid.

FIG. 3 is similar to FIG. 2 and shows the shim of FIG. 1 in position in the interlock.

FIG. 4 is a sectional view looking in the direction of line 4—4 on FIG. 3.

In FIGS. 27 and 28 of the Shoup Patent 2,054,102, referred to, there is shown an interlock which limits the number of candidates for any given office for whom a vote may be cast. For example, three persons may be running for an office for which only one person can be elected (such as mayor), or seven persons may run for three seats (such as city councilmen). The type of interlock referred to is better illustrated in FIG. 1 of Shoup Patent 2,293,669 and to which reference may be had for the necessary background. But, to make detailed reference to the last mentioned patent unnecessary, the pertinent parts of said patent are briefly described below, the reference numerals used being those which appear in FIG. 1 of Patent No. 2,293,669.

In this patent an interlock includes a vertical channel, locking pins 63 passing through the channel in vertically spaced relation, free moving balls, or rolls 62 and pull straps 61 passing between and extending outwardly of the rolls 62 and having wedges 64 disposed in the channel inwardly of the rolls. Play is provided between rolls 62 sufficient to permit one, or more, wedges to be inserted between the rolls when the corresponding strap is pulled out by turning a voting spindle in vote-casting direction. Referring to the part referred to as "Main Interlock" in Patent No. 2,293,669, it will be seen that there are four rolls and three pull straps between the uppermost pair of locking pins 63. It will also be seen that there is a vacant

space immediately below uppermost pin 63. This means that only one of the three pull straps can be moved outwardly because the wedge 64 of the first pull strap moved will fill the vacant space and will immobilize all of the other pull straps. Obviously, if the vacant space is doubled, two out of the three, or more, pull straps can be pulled out, and so on.

It is clear that the setup of an interlock for an election where, for example, seven candidates are running for a given office, will not be suitable for another election in which a fewer number of candidates are running for the same office. It can also happen that the setup for only one office need be altered. But, according to the disclosure of Patent No. 2,293,669, the number of pull straps which can be pulled out from any section of the interlock cannot be changed without pulling out all of pins 63 and removing rolls 62 to decrease the space which receives the wedges 64 of the straps which are pulled out. The time and labor involved in such a procedure, are almost prohibitive.

According to this invention, the capacity of the various interlock sections may be modified, within a wide range, without pulling out the locking pins or dismounting any other part of the interlock. This is accomplished by making the interlock sections big enough to accommodate the largest conceivable number of candidates and then reducing the space between the delimiting pins 63 by inserting shims which decrease the available play in the interlock section as needed. For example, and assuming that only five councilmen are replaced every year, the corresponding interlock section for the pull straps to be used in electing the five members of council, can be so made as to allow only five pull straps to be pulled out. But if, in a special election for councilmen, or if in a different election for a different office, only two candidates are to be voted for, additional shims can be introduced into the interlock channel further to decrease the play so as to limit the number of pull straps which can be moved out to two, and so on.

As will be seen from the Shoup Patent No. 2,293,669, the interlock is of U-shape in cross section and its limbs are provided with grooves, which receive the opposite heads of rolls 62. If the shim to be placed below, or above, or between rolls (to reduce the play between the rolls and, hence, the number of pull straps which can be moved out together) is rigid, and if it is provided with two opposed heads, which must enter the grooves, the shim cannot be inserted unless at least, the interlock section involved and those immediately above and below it have been dismantled. In other cases it may be necessary to dismantle the entire interlock which can be forty inches long and can be subdivided into a large number of units. In certain cases it may be necessary to dismantle a large portion of, or the entire, interlock before shims can be inserted or removed. According to this invention, I have produced a shim which can be readily inserted into, or removed from the channel of an interlock section without any dismantling of any part of the interlock.

The shim illustrated includes a handle portion 10 which carries a U-shaped element 12 formed of limbs 14 and 16 which are inter-connected by a relatively narrow arcuate section 18 whereby the limbs may be compressed towards each other as in FIG. 2. Limbs 14 and 16 are springy enough to return to the position of FIG. 1 when unrestrained.

The interlock to which the shim is applied is identical with that shown in the Shoup patents aforesaid, and the only parts thereof with which this disclosure is concerned are the grooves 20 which receive the opposite ends of rolls 62 which are interspersed between the pull straps. In the shim illustrated, one of the limbs, such as limb 16, is provided with a lug 24, the edge 26 of which slants as shown in FIG. 2.

When it is desired to reduce the capacity of a section of the interlock, that is, when it is desired to reduce the number of pull straps which can be moved by the rotation of the corresponding spindles, the round end of the shim is inserted into interlock. When, as shown in FIG. 2, lug 24 reaches the interlock opening, it slides against one edge 28 of the interlock. During this movement, the limbs of the shim are compressed and, as soon as lug 24 clears the edge of the interlock, it snaps out into adjacent groove 20 to lock the shim in position as shown in FIG. 3. To remove a shim, it is merely necessary to compress the limbs until lug 24 clears groove 20 and then to pull the shim out of the interlock.

For example, in one election it may be necessary to elect four out of nine candidates for the office of councilman and therefore the interlock section used will have nine pull straps and will have enough play to permit movement of four pull straps before the rest of the pull straps are immobilized. In another election, it may be necessary to use the same interlock section to vote for a number of candidates less than four. Without this invention, it will be necessary to dismantle and reassemble the interlock section to reduce the play, so as to permit the movement of the desired number of pull straps. This involves considerable time and labor and can only be effected in the shop. According to this invention, it is merely necessary to insert one shim for each pull strap to be immobilized. For example, if the interlock section is initially provided with enough play to permit movement of four pull straps and if it is desired to limit the number of movable pull straps to two, it is only necessary to insert two shims in the interlock section. When this is done, only two pull straps, instead of four can be used. It is evident that the shim of this invention can be inserted, or removed, instantly, without skill, without special tools, at any location and under all conditions.

What I claim is:

1. A shim for insertion through a passage defined by a wall, said shim comprising flat, co-planar parallel limbs and a flat, co-planar bight portion connecting said limbs, said shim being made of a resilient material whereby said limbs are movable relative to each other, a lug projecting laterally from one of said limbs, the width of said shim and said lug combined being greater than the width of said passage whereby one of said limbs must be moved to-

ward the other to compress the shim prior to insertion of the shim into said passage and whereby upon movement of said shim through said passage until said lug clears said passage, said limbs will resume their initial position and said lug will engage the edge of said wall to prevent reverse movement of said shim, the leading face of said lug being tapered in the direction of movement of said shim into the passage to facilitate insertion of the shim into the passage and the trailing face of said lug being square to prevent movement of said shim out of said passage without prior compression of the shim.

2. The combination, with a voting machine interlock of the type which has a side opening adapted to receive a given number of pull straps and is provided with enough play to permit movement, relative to the interlock, of a number of pull straps less than said given number; of means for varying the amount of play to vary the number of pull straps which may be moved relative to the interlock,

of a shim having a thickness substantially equal to the effective thickness of a pull strap, and a lug carried by a side of said shim and engageable with the interior of the interlock, detachably to secure said shim in said interlock, the combined width of said shim and said lug being greater than the width of said opening, said shim being resiliently compressible to a combined width less than the width of said opening to permit insertion and withdrawal of said shim into, and from, said interlock, while said shim is in the compressed condition, without moving, or removing, any pull strap.
